UNITED STATES PATENT OFFICE

RALPH R. ATKINSON, OF PRINCETON, INDIANA

MINE TIMBERING MACHINE

Application filed February 17, 1932. Serial No. 593,567.

The purpose of this machine is to have props loaded at the mine entrance and transported directly to their respective working places by the machine itself. When reaching the working place the machine will be lengthened out to its full capacity. Then with the endgate opened it gives free access to the carload of mine props and drilling equipment. The prop length will be measured by an assistant and called to the operator who will by that time have the prop holder set at a required prop length. The invention relates to the body and its appurtenances which are mounted on a constructed motor frame.

Figure 1 is a plan view of the machine in the position of travel mounted on one type of motor. Figure 2 is an elevated view of the machine in the position of travel mounted on one type of motor. Figure 3 is a plan view of the foundation plate of swinging gear and turntable which is made secure to the motor frame and forms a base upon which the remaining parts of the invention are projected. Figure 4 is a plan view of the thrust and guide block for the pony truck. Figure 5 is a vertical view of the thrust and guide block for pony truck. Figure 6 is a partial front vertical view of the pony truck showing guide frame and arms, elevating and depressing screw and the pony truck wheel. Figure 7 is a side vertical view of the pony truck showing the relative position of the thrust block and a broken section of the guide exposing the elevating and depressing screw. Figure 8 shows a vertical view of the endgate and the relative position of tools used in drilling and a side view of the combined endgate latch and prop hanger. Figure 9 gives a vertical view of the upper portion of the machine cargo body with the endgate opened exposing view of props ready to be cut as desired, and giving drillers free gate and the operator to props. Figure 10 is a plan view of the outer side of the outer shell of the body showing gear and turntable parts. Figure 11 is a plan view of the top of the outer shell of the body with the floor removed showing longitudinal screws

and swinging gears. Figure 12 is a plan view of the transmission. Figure 13 is a vertical half section of the gear and shaft arrangement connecting the transmission and longitudinal screws. Figure 14 is a vertical half section of gears and shaft connections, transmission and swinging gears. Figure 15 is a plan view of a detachable bar placing jack head. Figure 16 is a vertical back view of the detachable bar placing jack head. Figure 17 is a vertical end view of the demountable placing jack head. Figure 18 is a vertical half section of her placing jack. Figure 19 is a plan view of the drill holding head used for preparing holes for bars to be placed. Figure 20 is a vertical view of the jack head when fixtures are mounted. Figure 21 is a vertical view of the table extended in working position. Figure 22 is a vertical view of the prop length measuring gauge partly extended. Figure 23 shows a vertical view of the sliding prop holder. Figure 24 is a plan view of the guard rail in broken sections showing graduations which facilitates the prop length cutting. Figure 25 is a vertical view of the detachable roller on which rails are handled. Figure 26 shows a vertical half section of the band saw elevation adjustor.

The plate or base 1, Figure 3, is secured to the motor frame. On this base are mounted two arc plates or shoes 2, 2, on which another pair of identical arc plates or shoes 6, 6, Figure 10, slide during the time the body is being revolved horizontally. The revolving of the body is accomplished by the gears 3, 3, 3, Figure 3, which are mounted on shafts 4, 4, 4, meshing with internal gear 7, Figure 10, and gear 5, Figure 10, which is turned by shaft 8, Figure 10, on which is worm gear 9, Figure 11, in mesh with worm 10, through which square shaft 11 slides as the table 65, Figure 1, is extended in or out of the body shell which is keyed to gear 13, which is in mesh with gear 14, Figure 14. Keyed on shaft 15, Figure 14, on which miter gear 16 is keyed, which is in mesh with miter gears 17 and 18. These gears 17 and 18 are not keyed to shaft 19, but run free and are moved

to a meshed position by slip collars in housings 20 and 21.

Gears 17 and 18 are rotated by being engaged respectively by slot clutches 22 and 23, which are engaged to their respective gears by lever 25, and connected to lever 26 by a rod. The arrangement so operates that when gear 17 and slot clutch 22 enter gear 18 and slot clutch 23, they disengage and have sufficient sliding room so that neither are in gear and the lever is left vertical. Shaft 19 may be disengaged from the source of driving power by the snap-in clutch 24, operated by lever 27, of a commercial type, making it unlikely to start the turning gears until desired as this disengages shaft 19 from gear 28, which is keyed to shaft 19. This is in mesh with gear 29, which is keyed to shaft 30, and is connected to the driving power plant. The gear 31 is keyed to shaft 30, and in mesh with gear 32, which is free to turn on shaft 33, being connected to shaft 33 as desired by a snap-in clutch 34, which is operated by lever 35.

The gear engaging, disengaging and neutral arrangements in Figure 12 are identical in their workings. Shaft 33 turns slot clutches 36 and 37 and when engaged with miter gears 38 and 39 respectively, they cause miter gear 40 to rotate in the desired directions so as to cause the work table to be run out or in the body shell by revolving shaft 41, Figure 13, which is keyed to miter gears 40 and 42. Miter gear 42 is keyed to shaft 43, Figure 11, which is screw-threaded from thrust block 44 to the inner end of the shaft a portion of which is shown in Figure 11 by cutting away the guide pipe casing 53.

Shaft 43 has keyed to it miter gear 45, in mesh with miter gear 46, which is keyed to shaft 47 on which miter gear 48 is keyed and in mesh with miter gear 49, which is keyed to screw shaft 50. This is identical with screw shaft 43 being a screw through thrust block 51 to its end which extends the full length of the body and encased in a guide pipe 52. When shaft 43, is rotated, shaft 50 has a similar movement in or out of the thrust blocks 44 and 51. They have fixed bearings to the body shell 110, while the shafts are attached to the work table 65, Fig-

1. This causes the table to move as the shaft is thrust in or out through the turning of the shafts, 43 and 50, according to the direction of rotation.

During the time that the work table is being run in or out the pony truck, Figure 7, is in contact with the ground to support the weight of the extended end of the work table.

2. The pony truck consists of a wheel 54 and its frame 55, and guide arms 56, 56, as a unit so as to revolve free of the attached end; to which is attached in line of the guides a screw 57, which passes through the thrust screw and guide block shown in Figures 4

and 5, elevating or depressing a pony truck as desired by the turning of the hand wheel 58, which is fixed to screw 57, in either direction as the pony truck is to be lowered or raised.

In Figure 4, the square holes 59, 59 are to hold guides arms 56, 56, while they are allowed to slide up and down and as screw 57 is rotated through thrust block screw hole 60 causes an up and down motion as the thrust block, Figure 4, is secured to work table 65, Figure 1; thereby transmitting thrust up or down to the table as the wheel comes in contact with the ground or is in a raised position so as to be in the clear while the machine is being transported.

Figure 8 shows three sockets 61, 61, 61 into which roller 162, Figure 25, may be inserted at will to facilitate the handling of bar rails when barring is to be done. The circular openings 62, 62, Figure 8, admits sliding guard-rails 63 and 64, Figure 1, which slide in harmony with work table 65, Figure 1, being secured to work table 65 by standards 66, 66, Figure 1. Guard rail 63 differs from guard rail 64 in the respect that it is graduated in feet and inches of the zero mark being in alignment with the band saw 71, and the graduations increasing toward body shell 110, as shown in Figure 24, where props are stored. This enables the operator to set sliding prop holder 67 to be set at a desired prop length from the band saw 71, as the prop butt is snug in prop holder 67 and the end against prop stop 68, Figure 23. The band saw blade 116, Figure 2, is at the desired prop length ready to be cut. The prop hanger is held at a desired position on guide rails 63 and 69 by set screw 70, which is quickly set and loosened by the crank arrangement as shown in Figure 23.

The band saw 71 may be raised or lowered as shown in Figure 26, by the screw 72, which is keyed to miter gear 73, and is in mesh with miter gear 74, which is keyed on shaft 75. On this the wheel 76 is keyed and as the wheel is turned in the desired direction, the screw turns in thrust block arms 77, 77, causing them to be raised or lowered and they are fastened to the band saw frame, causing it to be raised or lowered to its desired position.

The carrying jack consists of a frame 79, hexagon hollow screw 80, in which hexagon 81 is free to be raised or lowered, and is held in a desired position by set screw 82, in crank form which is easily and quickly set and loosened at will. The screw column 80 has a lug 83, which slides in a slot in the frame 79 as the column 80 is raised or lowered preventing the screw 80 from turning on its longitudinal axis as it is acted on by gear 84, whose center portion is the thrust block for screw 80. Gear 84 is in mesh with gear 85, which is keyed to shaft 86, to which miter gear 87 is keyed meshing with miter gear 88.

which is keyed to shaft 89, which is connected to the traction motor of its driving power; the motor is reversible which gives a means of lowering and raising screw 80.

The collar 90 shown in Figure 19 is used to mount a drill upon and slides on the hexagon shaft 81, when it is extended and clamped by set screw 82. The screw 80 is raised until the point 91 is firmly embedded in the roof by the upward pressure of thrust gear 84. When the collar 90 is slipped to its desired elevation it is held so by the set screw 92. Where by holding the drill in the desired working position the cap plate 115 takes the upward thrust of gears 84 and 85. This jack is located on the center line of the traction motor frame in front of the circular end of body shell as shown in Figure 1 where point 97 is exposed.

The jack head shown in Figures 15, 16, 17, consists of three arms 93 93 94, and the crossbar 95, which has an opening 96, to fit 97, the cylinder end of shaft 81. The arm 94 is provided with a rectangular opening 98 in which a lug 99 is connected to the screw 160, which uses crossbar 95, as a thrust block. Screw 100 is crank shaped on the end, and crank 101 provides a means of turning screw 100, which moves lug 99 to and from crossbar 95 and vertical rail stops 102, 102. The lug 99 is forced against the rail by screw 100 as a vice holding the rail firmly against rail stops 102, 102 in its position to be raised to the roof by screw 80.

The endgate 105, Figure 8, is provided with suitable hangers for drill 103, drill post 104 and an extended electric cable 106 for carrying power to the drill. The endgate 105 is on hinges 107, 107, the opening 108, 108 allowing endgate 105 to pass prop hanger and endgate latch 109 as it is slightly raised so as to be disengaged from square socket 111 and swung in line with body shell 110, Figure 2. After endgate 105 is closed it is locked by swinging prop hanger and latch 109, by being swung against the endgate and allowed to seat in socket 111. The sockets 61, 61, 61 are used to insert the swivel roller 162 shown in Figure 25. This roller facilitates the handling of barring rails.

The measuring gauge shown in Figure 22 has two pointed rods 83, 83 one in each end to insure measurement in loose material to a solid footing where prop is to be set, thus giving a measure to a firm base. The upper part 85 may be raised or lowered and held as desired by set screw 84 in making measurements. The upper part 85 fits in to lower frame 86, making the measuring gauge compact and protecting the upper end when the gauge is not in use.

In Figure 21, is shown the method of current supply of work table motor. The plug boxes 112 and 113 are connected by detachable electric cable 114. Plug box 112 is con-

nected to traction motor fuse box by a suitable conductor supported by traction motor frame. This cable 114 shall be of such length that it will allow current to be supplied to the table motor when tables 65 is fully extended. 70

The reel of electric cable is usually placed on top of a mine motor frame as shown in Figures 1 and 2 as #117.

A steel box with a removable lid is to contain the detachable jack heads as shown by 75 Figures 15, 16, 17 used to place bars and removable rail roller 162, Figure 25. Figure 23 is to be secured to the platform on head end of the traction motor as shown in Figure 1 as #118. 80

The motor mounted on work table will be encased in a metal box as shown in Figure 1, as 119, the fuse box located as 120, and the transmission in its box 121. 85

I claim:

In a mine timbering machine, the combination of a self-propelled truck, a compartment on said truck adapted to carry mine timbers, a self-contained sawing unit mounted on one end of the truck and having sliding telescopic connection with said timber compartment, a vertically adjustable jack mounted on the opposite end of said truck, a motor on said truck, mechanism driven by said motor for propelling the truck, mechanism driven by said motor for actuating said jack, and a separate motor on said sawing unit for actuating said saw. 90
